UNITED STATES PATENT OFFICE.

PETER HOITSMA, OF PATERSON, NEW JERSEY.

SCAFFOLD MACHINE.

Application filed February 25, 1922. Serial No. 539,174.

To all whom it may concern:

Be it known that I, PETER HOITSMA, a citizen of the United States, residing at Paterson, in the county of Passaic and State of New Jersey, have invented certain new and useful Improvements in Scaffold Machines, of which the following is a specification.

This invention relates to climbing supports and particularly to climbing supports for use in scaffolding required by workmen in constructing or working upon a building, and where the scaffolding includes one or more (usually at least two) uprights spaced from the wall of the building. The object of the invention is to provide a climbing support which will obtain a secure hold on the upright and be at all times proof against unintentional downward slipping thereon and which the workmen, while supported thereby, can operate with facility so as either to climb or descend relatively to the upright and which will further be quite simple in construction.

In the accompanying drawings, Fig. 1 is a side elevation of an upright and shows the improved climbing support thereon in vertical section;

Fig. 2 is a sectional view on the line 2—2, Fig. 4, looking toward the right;

Fig. 3 is a plan view of two of the improved supports arranged on two uprights, which appear in section, and planking resting on the supports and forming therewith and with the uprights a scaffold;

Fig. 4 is a side elevation of what is seen in Fig. 3.

Let *a* designate one of the uprights which will rest on the ground and preferably consist of wooden lengths (as 2 x 4's) and further will be progressively extended upwardly to any desired height by lap-jointing or otherwise joining the ends of said lengths, the uprights being secured to the building at successive elevations by braces (not shown). Usually there will be at least two of these uprights and two of the improved supports, one on each upright, and the supports will carry planking as shown in Fig. 3.

Each support or supporting structure is constructed as follows, having reference to the particular example shown in the drawings: Two strips of angle iron *b* are bent

at corresponding points in their lengths so that each forms an acute angle, one arm *b'* of which is shorter than the other *b* and is 55 adapted to bear flat against one upright face of the upright *a*, so that it stands vertically. *c* is a horizontal brace which connects the upper ends of the two arms *b'*, *b*. Each thus-bent strip *b* and its brace *c* are rigidly 60 connected together and to the other strip and brace, so as to form what I term the "load-carrying" member, by bolts *d* which penetrate spacing sleeves *e* arranged between the two strips *b*.

A bolt *f*, extending through the two apices of the strips *b*, affords a pivot for a shackle member *g*, which is a strip of metal bent into the form of the letter **U** and is adapted to embrace the upright *a*, in such manner 70 that its free ends traverse the latter. Connecting the extremities of the member *g* is a gripping device *h* adapted to bear against the adjoining face of the upright and which in order to obtain an effective hold thereon 75 has a biting edge *h'* adjacent thereto, as by being square in cross-section, said device being kept from turning by being fitted in square holes in member *g*. The load-carrying member affords as to its portion *b'* a 80 device which coacts with device *h* to grip the upright when the weight of said member is on the shackle member and *h* obtains a hold on the upright. The shackle is normally urged upwardly on bolt *f* as a pivot 85 by a spring *i* which is coiled about the bolt and has one end bearing upon the bolt *d* and the other end against the bend or inner end of the shackle. The construction is such that the supporting structure may easily slip 90 upwardly on the upright but immediately gravity becomes active to move the structure downwardly, it obtains a perfectly secure grip on the upright on account of the spring. As will appear, the grip thus effected can 95 however be disestablished by pressing downwardly on the end of the shackle member having the gripping device *h*.

Given a supporting structure having the foregoing or any other means to grip the 100 upright which is normally freely slideable upwardly but not downwardly thereon, I provide a lifting means, as follows, which in the present example also in a measure co-

acts, when not lifting, with said gripping means to sustain the load. A shackle member j is formed by a strip bent into the shape of the letter **U** and having grips k' k^2 connecting its two side portions, said shackle member being adapted to embrace the upright so that the latter stands between the two grips; one of the grips, as k' , may be a plain bolt, while the other or relatively outer one, k^2 , is preferably a bolt having a square cross section, and arranged so as to present one of its edges k^3 as a biting edge to the upright, being kept against turning by being fitted into square holes in the shackle. It will be apparent that when both grips engage the opposite faces of the upright and a load is applied to the shackle at a point thereof nearer one grip (as k') than the other the shackle will grip the upright and oppose downward movement of the load—positively, if the other grip has an effective hold on the upright. A fulcrum support is provided on the shackle, the same in this instance consisting of a pair of links l which are pivotally suspended from a cross-bolt m connecting the sides of the shackle and having their lower ends connected by a bolt n on which is a roller n' . On the bolt n is fulcrumed a lever o formed by two metal strips the outer ends of which are rigidly connected by a bolt p and a spacing sleeve q penetrated by the bolt and arranged between the strips and the inner ends of which are pivoted on a bolt q' outwardly of the upper ends of the portions b' of the load-carrying member, in which the bolt q' is arranged. The shackle is preferably normally urged to turn on the pivot afforded by bolt m in the direction to elevate the grip k^2 by a spring r which is coiled about the bolt m and has one end overlapping the bend or inner end of the shackle and the other end engaged with a cross bolt s joining the links l .

45 Operation: Normally the load is supported by the means b g ; the load-carrying member b is at this time kept from tilting away from the upright on f as a pivot by the contact of n with the upright so that to this extent at least, and even if the gripper j were moved so as to depress its grip k^2 and thus cause a release of the gripper, the lifting means coacts with the means b g to sustain the load. To cause the supporting structure to climb, the operator, who is on the platform afforded by the planking t , depresses the free end of lever o , which at this time is supported by the means j l , thereby raising the load-carrying member and at the end of the stroke the means b g assumes a fresh grip on the upright. To rise another stage, the lever is elevated, thereby raising the gripper j to a new elevation (where it instantly assumes a fresh grip on the upright both because of the specified re-

lation of the two grips to each other and to the pivot m and because of the means r operating to elevate the free end of the gripper), and on now depressing the lever the lifting operation is repeated as before.

In descending, the operator sits on the planking t shown in Figs. 3 and 4, straddling the upright, with his feet on the ends of the gripping device h . He then raises the lever to cause the upright to be gripped with a slip grip between q' and n' , and having released the shackle g with his foot and the gripper j with his free hand allows the supporting structure to fall, subject to such slip grip, whereupon he releases the shackle so that the supporting means becomes locked to the upright at the new or lower elevation. (Or the upward pressure on the lever whereby the slip-grip is controlled may be effected by utilizing a rope v which will be lashed to the upright as shown in Fig. 4 and passed around the bolt p of the lever and held under control at its free end by the operator). Quite independently of the shackle and gripper, therefore, the lever o with its gripping device n n' is a factor useful in effecting controlled descent. Descent may also be effected step by step thus: by depressing the lever, having first released the gripper, and allowing the gripper to re-engage the upright in the new or lower position, and then, while holding the shackle released with the foot, allowing the supporting structure to descend a stage subject to the operator's control effected through the lever, and finally permitting the shackle to re-engage the upright; and so on, step by step downwardly.

To afford a foot-hold on the shackle g and a handhold on the gripper j the ends of the devices h and k^2 may be prolonged as shown in Fig. 2.

To adapt the shackle g and gripper j to uprights of different cross sections additional holes u may be provided in them for the reception of the devices h and k^2 .

Having thus fully described my invention, what I claim as new and desire to secure by Letters Patent is:—

1. In combination, with an upright and with a load-carrying member at one side of the upright having means to engage the upright normally freely movable upwardly but not downwardly on the upright, lifting mechanism including a lever pivotally connected with said member and movable upwardly and downwardly relatively thereto, and means in which the lever is fulcrumed having a gripper engaging the upright and also normally freely movable upwardly but not downwardly thereon, said lever having means to bear laterally against the upright.

2. In combination, an upright, a load-carrying member having means to engage the upright normally freely movable upwardly

but not downwardly with respect thereto, and lifting means including a shackle having grips engaging opposite faces of the upright, a lever pivotally connected with said member, a link pivoted to the shackle nearer one grip than the other and affording a fulcrum support for the lever, and a spring

connecting the link and shackle and normally acting to turn the shackle on the pivot between the latter and the link in the direction to elevate the grip which is remote from the link. 10

In testimony whereof I affix my signature.

PETER HOITSMA.
